US0D1094700S

(12) **United States Design Patent** (10) **Patent No.:** **US D1,094,700 S**
(45) **Date of Patent:** **** Sep. 23, 2025**

(54) **ON-BODY FILLABLE INJECTOR**

(71) Applicant: **Becton, Dickinson and Company**,
Franklin Lakes, NJ (US)

(72) Inventors: **Vincent Delobelle**, Franklin Lakes, NJ (US); **Eleanor Bainton**, Kineton (GB); **James Leslie Rhodri Jones**, Pencader (GB); **Daniel Paul Jenkins**, St Albans (GB); **Zoe Georgina Armstrong**, Leamington Spa (GB); **Malcolm Stanley Boyd**, Franklin Lakes, NJ (US)

(73) Assignee: **Becton, Dickinson and Company**,
Franklin Lakes, NJ (US)

(**) Term: **15 Years**

(21) Appl. No.: **29/967,947**

(22) Filed: **Oct. 14, 2024**

Related U.S. Application Data

(62) Division of application No. 29/881,356, filed on Dec. 30, 2022.

(57) **CLAIM**

The ornamental design for an on-body fillable injector, as shown and described.

DESCRIPTION

FIG. 1 is a front perspective view of an on-body fillable injector, showing our new design;

FIG. 2 is a rear perspective view thereof;

FIG. 3 is a front elevation view thereof;

FIG. 4 is a top plan view thereof;

FIG. 5 is a left side elevation view thereof;

FIG. 6 is a right side elevation view thereof;

FIG. 7 is a rear elevation view thereof; and,

FIG. 8 is a bottom plan view thereof.

The broken lines in the drawings depict portions of the on-body fillable injector that form no part of the claimed design.

1 Claim, 7 Drawing Sheets
